UNITED STATES PATENT OFFICE

97,863

DESIGN FOR A LADY'S SPORT GARMENT

Martha A. Pietzsch, New York, N. Y.

Application July 29, 1935, Serial No. 57,856

Term of patent 3½ years

To all whom it may concern:

Be it known that I, Martha A. Pietzsch, a citizen of the United States, residing in the city of New York, county of New York, and State of New York, have invented a new, original, and ornamental Design for Lady's Sport Garment, of which the following is a specification, reference being had to the accompanying drawing, forming a part thereof.

In the drawing—

Fig. 1 is a front view of the garment including the skirt;

Fig. 2 is a rear view of the garment including the skirt;

Fig. 3 is a front view of the garment with skirt removed;

Fig. 4 is a rear view of the garment with skirt removed; and

Fig. 5 is a rear view of the garment with skirt removed and with the rear panel lowered to illustrate the covering relation of the side pleats with respect to the panel securing means.

I claim:

The ornamental design for a lady's sport garment as shown and described.

MARTHA A. PIETZSCH.
